UNITED STATES PATENT OFFICE.

JOHN H. TATUM, OF AMARILLO, TEXAS.

FRUIT-SELLING SLOT-MACHINE.

955,718.

Specification of Letters Patent. Patented Apr. 19, 1910.

Application filed May 28, 1909. Serial No. 498,874.

To all whom it may concern:

Be it known that I, JOHN H. TATUM, a citizen of the United States, residing at Amarillo, in the county of Potter and State 5 of Texas, have invented new and useful Improvements in Fruit-Selling Slot-Machines, of which the following is a specification.

This invention relates to coin controlled 10 vending machines.

One object of the invention is to provide an apparatus of this character adapted more particularly for vending oranges and apples in which the operating mechanisms are so 15 constructed as practically to preclude disarrangement even when roughly used, and in which any attempt to "beat" the machine by the employment of a coin other than one of a predetermined diameter, will 20 positively be prevented.

A further object is in a novel manner to adapt the delivery mechanism to vary the number of oranges or apples dispensed at one operation, thereby measurably to extend 25 the range of usefulness of the apparatus, inasmuch as one can be made to accomplish the work of two.

With the above and other objects in view, as will appear as the nature of the invention 30 is better understood, the same consists in the novel construction and combination of parts of a coin controlled vending machine, as will be hereinafter fully described and claimed.

In the accompanying drawings forming a part of this specification, and in which like characters of reference indicate corresponding parts, Figure 1 is a view in side elevation of the machine showing one of the side 35 walls of the casing broken away for the purpose of disclosing parts of the invention. Fig. 2 is a side elevation of the lower portion of the machine showing one of the sides of the casing removed. Fig. 3 is a detail vertical section taken through a portion of the machine on a line with the plunger. Fig. 4 is a detail horizontal section taken on the line 4—4 of Fig. 3. Fig. 5 is a view similar to Fig. 3 showing the catch 40 of the rock shaft engaged with the plunger.

Fig. 6 is a detail section taken on the line 6—6 of Fig. 5.

Referring to the drawings, 1 designates generally the casing of the apparatus, which may be constructed of any suitable material, 55 and is provided in its top with a hinged door 2 through which the fruit is supplied to the vending apparatus.

Arranged within the casing is a feed chute embodying a hopper 3 and an approximately 60 U-shaped tube or pipe 4 which is of a diameter to permit ready passage therethrough of the fruit without danger of sticking. Of course it will be understood that in supplying the fruit to the feed chute, it will 65 be sorted so that there will be no danger of clogging the tube.

The discharge end of the feed chute, as shown in Fig. 4, is composed of a plurality of spaced sections 5 and 6, although this 70 number may be increased if found necessary or desirable, the object of this arrangement being to permit the apparatus to discharge one or two apples or oranges at each operation. 75

Arranged to work between the sections 5 and 6 are two cut-offs 7 and 8 each of which embodies a circular head that constitutes the cut-off proper and an arm 9 and 10 respectively. As shown in Fig. 2, when the 80 head or cut-off is in position to intercept passage through the feed-chute, the cut-off 8 is in a position to permit passage through the chute thus to allow a fresh charge or supply of fruit to assume a position for discharge upon a subsequent operation of the apparatus. The arms 9 and 10 are mounted upon a shaft 11 which is supported upon a pair of standards 12 secured to the base 13 of the apparatus, and are held against lateral movement thereon by collars 14 and 15 that are held rigid on the shaft by set-screws 16. As will be observed by reference to Fig. 1, the shaft 11 extends a considerable distance beyond the arm 10, the object of 85 this arrangement being to permit of the arm being shifted to bring the head 8 into co-operative relation with either of the spaces between the tube sections 5 and 6. When 90 adjusted as shown in the above figure, only 95 100

one orange or apple will be discharged at a single operation, but when shifted to bring the head within the space between the section 5 and tube 4, two apples or oranges 5 will be discharged.

The arms 9 and 10 extend rearward some distance beyond the shaft 11 and are pivotally connected with a pair of cranks 17 and 18 that are bolted to a shaft 19 journaled in 10 standards 20 secured upon the base 13. The shaft 19 extends beyond the crank 18 a distance equal to the adjacent shaft 11, and the crank is adjustable on the shaft in order to permit of the arm 10 being shifted for the 15 purpose above described. The shaft 19 is provided with an intermediate enlarged portion 21 from which projects an arm 22, and connecting with one end of this arm is a coiled spring 23, the other end of which is 20 secured to a bracket 24 on the base. The function of this spring is to cause the arms normally to occupy the position shown in Fig. 2, that is in which the discharge end of the chute is intercepted by the head 7 to prevent 25 the escape of fruit.

As shown in Fig. 5 the base 13 is formed with two passageways 25 and 26, arranged in alinement, and in the former is disposed a push rod 27 the outer end of which projects beyond the casing and is provided with a knob 28. The intermediate portion of the rod carries a head 29 which is adapted to fit within the passage way, and against which bears one end of a coiled spring 30, the other 30 end of which bears against the inner wall of the passage way 25, and operates normally to hold the rod in the position shown in Fig. 2.

The inner end of the push rod, when 40 moved to the position shown in Fig. 5, bridges a vertical slot 31 arranged above which, and extending to the top of the casing, is a coin receiving tube 32 which is of a size to accommodate a nickel, but no larger 45 coin. The slot 31 extends entirely through the base, but its lower end is constricted as at 33 in order to prevent the escape of a nickel, but to permit the passage of any smaller coin, such as a dime or a cent.

50 Arranged for sliding movements within the passage way 26 is a plunger 34 provided with a longitudinal orifice 35 in which the push rod will be received when no coin is within the slot 31, and thus prevent operation of the machine.

Secured to the shaft 19 is a depending arm 36 provided at its lower end with a longitudinal slot 37, and this slot is engaged by a pin 38 carried by the inner end of the 60 plunger 34, which latter is provided with a longitudinal slot 39 to receive the arm. At a point intermediate the ends of the plunger rod is arranged a notch 40 that is designed

to be engaged by a catch 41 carried by a rock shaft 42 mounted in standards 43 secured to the base, thus to hold the plunger rod in the position shown in Fig. 5 to permit the push rod 27 to move away from the nickel and permit the same to escape through a slot 33 in the base into a chamber 70 provided for its reception. The catch 41 is caused automatically to engage with the notch 40 by a coiled spring 44, one end of which is secured to the upper portion of an arm 45 rigid with the shaft 42, and the 75 other end of which is secured to the shaft 11. In order to throw the catch out of engagement with the notch, and in order to permit the plunger to resume its normal position, there is a wire link 46 provided, the inner 80 end of which is bent upwardly and rearwardly and passed through a slot 47 adjacent to the upper end of the arm 45, and the forward end of which is bent downwardly and passed through a keeper 48 on the 85 upper side of the push rod. This keeper is of such length as to permit the push rod to be moved inward a distance sufficient to actuate the cut-offs before its outer bend 49 will engage with the link, thus to insure the 90 proper actuation of the cut-off. Upon release of the push rod, the spring 30 will force it outwardly, and thus bring the inner bend 50 of the keeper into engagement with the link, and thereby rock the arm 45 and 95 automatically lift the catch 41 out of engagement with the seat.

In the operation of the device, the feed chute is filled with oranges or apples of uniform size, and as the cut-off 7 will be in the 100 position shown in Fig. 2, the discharge end of the chute will be closed. Upon the nickel being dropped down the tube 32, and upon inward movement being imparted to the push rod, the plunger 34 is moved inward, 105 and swings the arm 36, thereby rocking the shaft 19 and depressing the cranks 18 with the result that the cut-off 7 will be lifted upward a sufficient distance to clear the discharge mouth, while at the same time the 110 cut-off 8 will check the escape of fruit. When the fruit is released it passes into a receptacle 51 arranged at one side of the casing. During this operation the catch 41 will engage with the seat 40, and hold the 115 plunger against rearward movement until the push rod has moved a sufficient distance to free the nickel, and to actuate the link in the forward direction, whereupon the plunger will be released and resume its normal position.

From the foregoing description it will be seen that while the improvements herein defined are simple in character, they will be thoroughly efficient for the purposes designed, and will co-act in the production of 125

an efficient and reliable form of vending machines. The bottom of the hopper 3 is inclined downwardly toward the upper inlet end of the pipe 4, and as shown the said bottom is provided with a passage which is disposed immediately in line with said inlet end of the pipe 4.

5 I claim:—
A vending machine embodying a feed chute comprising a plurality of spaced sections, a plurality of shafts, adjustable cutoffs

mounted to rock on one of the shafts, operating means connecting the other shaft with the said cutoffs, a plunger for revolving the shafts to actuate the cutoffs, and means for 15 actuating the plunger.

In testimony whereof I affix my signature in presence of two witnesses.

JOHN H. TATUM.
